UNITED STATES PATENT OFFICE

107,726

DESIGN FOR A DRESS

Elizabeth Noest, Brooklyn, N. Y.

Application November 12, 1937, Serial No. 72,819

Term of patent 3½ years

To all whom it may concern:

Be it known that I, Elizabeth Noest, a citizen of the United States, residing at 309 96th Street, Brooklyn, in the county of Kings and State of New York, have invented a new, original, and ornamental Design for a Dress, of which the following is a specification, reference being had to the accompanying drawing, constituting a part thereof.

Fig. 1 is a front view of the dress.

Fig. 2 is the rear view of the dress as shown in Fig. 1.

The characteristic feature of my design resides in the combination on the tucked dress disclosed of the braided lace trim on the sleeves and front neck portion in association with the specific belt and blouse trim as shown.

I claim:

The ornamental design for a dress, substantially as shown and described.

ELIZABETH NOEST.
